CARTRIDGE CONTAINER MACHINE

August G. Liebmann, Washington, D. C., assignor
of one-half to Harry A. Blessing, Washington,
D. C.

Application July 6, 1942, Serial No. 449,943

5 Claims. (Cl. 93—55.1)

The present invention, styled "Cartridge container machine," has for its principal objects the forming of paper containers from tubular paper or other suitable material.

A further object is to insert the tubular stock material into a movable matrix or mold, and to cut off a piece of the same; furthermore to stuff or load the said piece and to crimp the ends of the piece to hold a disc of similar material enclosed upon the contents.

The primary object therefore of such a mechanical assemblage is to provide an inexpensive method for the forming, loading and closing of containers to hold surgical dressings, lint, gauze, etc., condiments, etc.; tobacco or any other dry or semi-dry products, chiefly dehydrated vegetable foods to meet the prevailing civil and military conditions now confronting the Nation.

As dehydrated foods must not be crushed or pulverized, a special method of packing and a special container must be employed, and so far as I am aware no such container has been provided. A container of this type to be used with this and made by this machine may be found disclosed in my copending application, Serial No. 472,640 filed January 16, 1943.

Other objects will appear in the following specification and claims and the subjoined drawings forming a disclosure of my invention.

Figure 1 is a side elevation of the assemblage.

Figure 2 is a cross section of the movable parts of the assemblage, showing the movable matrix and sequence of operation at one end and the complementary loading, stuffing and closing means at the other.

Figure 3 is a fragment of the top plan view of the compression feed, showing the ramrod carried by the guides, cutoff tool, etc.

Figure 4 is an inside end view of the assemblage, in elevation, showing the related position of the matrix, cross head, guides, crisper yokes and the cylinder to activate the matrix.

Figure 5 is a top plan view of the matrix, partly in section, with fragmentary view of location of the crimping means.

Reference now being had to the numerals, as follows: In Fig. 1 the bed plate 1 is supported by legs 2. Mounted on the bed plate 1 at one end is a compression cylinder 4 having a piston therein 3 and connected to the tubular piston rod 5, and bearing against a compression spring 6, visible in Fig. 2. The forward end of the cylinder 4 is provided with a conical head-yoke 7, serving to guide the tubular rod 5, and adapted to house the spring 6, when piston is forced the full length of 55

travel, the spring 6 serving to return the piston 3 and rod 5 to initial position as shown when the fluid pressure is relieved.

The fluid pressure referred to is fed through a pipe 8, and the release of pressure is handled through the same. The pipe 8 is connected through the cutout cock 9, to main reservoir 10 and the same is connected to an air compressor and motor hereinafter fully described.

10 Mounted upon one end of the bed plate as before stated is the compression cylinder 4, having a piston 3, see Fig. 2, and a hollow tubular rod 5; and mounted upon the opposite end of the bed plate is a pair of guides designated 13 and 13a, see Fig. 4, adapted to secure a matrix 14 in a slideable mounted position. The matrix is thus slid by means of a piston rod 15 and complementary piston 15a working in a cylinder 16.

Disposed parallel to the bed plate and superimposed thereto, are the guides 17 and 17a, connecting the compression cylinder 14 and the matrix guides 13 and 13a of the matrix assemblage 14, for vertical shift. The guides 17 and 17a have a cross head mounted thereon for lateral shift.

15 20 25 The said cross head 18 is provided with a split collar 19, Fig. 2, and lever and screw 20 to clamp the cross head 18 to the tubular hollow cylinder rod 5 as, when and if required.

Thus the cross head may be manipulated or 30 handled by the fluid pressure to compensate for different types of operation of loading and closing containers.

The cross head 18 is provided with a ramrod 19a mounted thereon for stuffing the tubular sections 35 cut off and reposing within the matrix 14. Mounted on the matrix guides 13 and 13a are crimping means 20 and 20a carried by yokes 21 and 21a secured to the guides 13 and 13a. These crimping means are adapted to seal the ends of 40 the tubular section after loading and while it is in the matrix 14.

In Figure 2, a cross section of the matrix is shown with the sequence of operation above noted. The matrix 14 is provided with a series of apertures and in sequence of the vertical rise, the tubes reposing in the said apertures in 23, the tube 22 is just cut off, loaded and stuffed in 23a, and crimped in 23b. The hollow piston rod 5 extends forward and rearward of the piston 3, the rearward portion extending through a fluid pressure stuffing box 24, having a chuck 25 which is provided with slideable grip pins 26 and 26a adapted to grip the tubular stock and facilitate the rotary movement of the same, tubular stock used with comfortable easy sliding fit within the matrix 14

and apertures 23, to compensate for swelling under pressure when loaded, and to prevent undue tightness, to forbid easy discharge from the aperture of the matrix.

Figure 3 shows the cutoff wheel mechanism 27 adapted to sever the tubular stock 22 when in position within the apertures of the matrix 14. This is accomplished by manual rotation of the tube stock gripped by the chuck assemblage 25, and pins 28 and 28a of the invention.

Figure 4 shows the inside view of the elevation of the matrix 14 mounted for vertical sliding movement within the guides 13 and 13a and carried superimposed and secured to the bed plate 1, shown in cross section and carried by the legs 2, et seq., the fluid pressure shift-cylinder adapted to activate the same. In this view the cross head mounted on guides 17 and 17a is shown in section, the crimpler yoke 21 fixed to guide frame 13 and 13a by means of dowels 28 and 28a.

Figure 5 is a top plan view of the matrix 14, partly in section, showing one of the crimpers 28 as also shown in Figure 1.

The tool comprises a crimpler carried by the yoke 21 provided with a threaded shank 29 having a hand wheel 30 to actuate the same, the opposite end of the shank 31 being a smooth taper broach, having a pin 32 rotatably mounted transversely thereof and piercing the same. The pin 32 is provided with grooves 33 and 33a conforming to and meeting the very same or flush joint of the surface of the taper broach of the shank designated 31.

When the shank 29 is advanced by reason of its threaded portion, the taper broach of its opposite end engages the inner walls of the tube stock 22, and the rotary movement and advance causes the grooves 32 and 32a to engage the ends of the tube stock and bend them inwardly to conform to the taper broach, thus ironing the ends inwardly and serving to close the same against the predisposed wads, disks or fitting, by crimping inwardly the ends of the said tubular stock. The automatic lock, as shown in Figure 5, is hereafter more fully described to secure the matrix 14 in different positions of shifted adjustment.

The operation of the assemblage is as follows:

Ordinary paper tubing or other suitable material 22 of conventional manufacture and design is inserted through the chuck 25 and the piston rod 5 to confront one of the apertures of the matrix 14. This material is cut off by holding the cutoff wheel 27 in contact with the tube by manual control, meanwhile rotating the chuck wheel 25. Compressed air advances the piston rod 5 to make the contact and feed the tube into the aperture. Release of compressed air, exhausted through pipe 32, then trapped behind the piston 3 in cylinder 4, allows the compression of the spring 6 to return the piston and rod to initial position as shown in Figure 2.

Thus the operation in sequence is as follows: Mounted in a convenient place upon the bed plate 1 is an electric motor 12, coupled by a belt 34 to an air compressor 35, air from the compressor as led by a pipe 36 to the reservoir designated 10, thence through pipe 8, through the three way cock 9 to control the fluid pressure, to activate either piston and cylinder designated 4 and 5 or 15 and 16 respectively.

Fluid pressure is passed either by exhaust or trapped air, in cylinder 4 through train pipe 37, closing check valve 39 and opening spring weighted check valve 40, and passing into cylinder

16, activating the piston 15a and its rod 15 and moving upward the matrix 14.

As the matrix 14 moves up or down, notches 34 shown in dotted lines, Fig. 5, insure registry of the apertures of the matrix with the rod 5, the ram rod 19a and the crimpers, by providing seats for the registering rod 41. Rod 41 is seated by spring 43 and retracted by air pressure acting on piston 42 in cylinder 48. Air enters the space 47 to the left of the piston 42 from pipe 44 (Fig. 1) through port 45. The ramming pressure in cylinder 4 is regulated to suit the material to be packed, being for example, high for surgical dressings, low for dehydrated foods.

To prevent displacement of matrix while loading, pressure is relieved by exhaust through cock 38, thus diminishing pressure in cylinder 16 and allowing the matrix 14 to remain securely locked. To unlock the matrix 14, a return of full feed of fluid pressure passes through the weighted check valve 41 into the cylinder 16, this flow being more rapid than the branch pipe locking means of piston and rod 42 and 42, but as the pressure builds up and backs through the branch pipe and through port 45 in the housing cylinder 46 of the same, this back pressure bearing against piston 47 in the cylinder counteracts the automatic compression of the spring 43 and withdraws the piston from the notch and unlocks the matrix 14, allowing it to move to next position where it is checked, and retarded by a manual reduction in pressure as before stated.

By slight exhaust and relief of pressure through the port 40a of the three way cock 38 the trapped fluid is released through check flap valve 39 and exhausted; thus, the matrix remains locked until the piston 42 is displaced by the building up of back pressure to counteract the compression of the spring 43 of the lock mechanism. Thus in sequence of rise and fall of the matrix 14, the same is securely and precisely locked for the uses and purposes named. In Figure 2, the matrix 14 with aperture 23b is shown in crimped position of the tube section of container, aperture 23a in loading position to register with ramrod 19a.

Having thus explained my invention and the operation thereof, what I claim is, viz:

1. In a packaging machine, a frame, reciprocating means guided on said frame for feeding tubing therealong, manual means for rotating the tube feeding means, manually projected means for cutting-off said tubing while rotating, an apertured head-block for receiving cut-off lengths of tubing, guides for said head-block for guiding it transversely of said frame, crimping dies carried by said guides for crimping cut-off lengths of tubing in an aperture of said head-block and power means for causing said feeding movement of said head block.

2. In a packaging machine, a frame, reciprocating means guided on said frame for feeding tubing therealong, manual means for rotating the tube feeding means, manually projected means for cutting-off said tubing while rotating, an apertured head block for receiving cut off tubing, guides for said headblock for guiding it transversely of said frame, crimping dies carried by said guide for crimping cut-off lengths of tubing in an aperture of said head block, power means for causing feeding and transverse movement of said head block and locking means for the head block rendered inoperative during a power cycle.

3. A packaging machine, comprising a frame,

a cylinder on said frame, clamping means connected to a piston in said cylinder for holding and rotating tubing, a ramrod connected to said piston, guides on said frame arranged at right angles to the axis of the cylinder, an apertured block guided in said guides, said apertures being in register with said ramrod and said tube holding means, crimping means carried by said head block guides in registry with another aperture of said head block and means for applying pressure to said piston to cause reciprocating movements thereof.

4. A packaging machine comprising a frame, guiding means on said frame for guiding a tube feeding member for movement along the frame, other guiding means arranged transversely of said frame, an apertured head-block movable along said latter guide means, means for rotating the said feeding means, means for cutting off a tube held and rotated by same feeding means, crimping means carried by said laterally disposed guide and power means for reciprocating the

tube feeding means and for moving the said head-block.

5. In a packaging machine comprising a frame, a cylinder on said frame with its axis parallel thereto, a piston in said cylinder, a spring for moving said piston in one direction and means for admitting pressure to the opposite side of said piston to move it against the force of said spring, said piston having means for clamping tubing, guides on said frame arranged transversely of the axis of the piston, an apertured head-block movable on said guides and connected to a piston, a cylinder for said later piston, locking notches in said head-block arranged in registry with said apertures, a locking pin for engagement with said notches, fluid pressure means for operating said locking pin into and out of engagement with said notches, and means for connecting fluid pressure to said first named cylinder and for conducting fluid from said first named cylinder to the second and third named cylinders.

AUGUST G. LIEEMANN.
